BINOCULAR BODY FOR MICROSCOPES

John T. Armbruster, Niagara Falls, N.Y., assignor to
American Optical Company, Southbridge, Mass.

Filed Feb. 8, 1965, Ser. No. 83,733

Term of patent 14 years

(Cl. D57—1)

FIG. 1 is a front perspective of a binocular body showing my new design the opposite side being substantially the same in appearance;

FIG. 2 is a rear perspective view of the assembly shown in FIG. 1;

FIG. 3 is a plan view of the binocular body; and

FIG. 4 is a side elevational view of the binocular body. The broken line showing of the microscope frame and related parts are for perspective purposes only.

I claim:

The ornamental design for a binocular body for microscopes, as shown and described.
